UNITED STATES PATENT OFFICE

2,666,310

HOLDER FOR BOTH FLAT BOTTOM AND CONICAL PAPER CUPS

Howard Hill, Easton, Pa., assignor to Dixie Cup Company, Easton, Pa., a corporation of Delaware

Application June 6, 1950, Serial No. 166,354

2 Claims. (Cl. 65—61)

1

This invention relates to improvements in a holder for both flat bottom and conical paper cups, the holder being highly desirable in a small size for dispensing sample drinks in paper cups, and for use in a larger size at soda fountains and similar places where drinks are dispensed commercially, although the invention will have other uses and purposes as will be apparent to one skilled in the art.

Heretofore, it has been the custom to provide one form of holder for flat bottom paper cups, and another form of holder for conical paper cups. Difficulty, inconvenience, aggravations and embarrassment have sometimes resulted, however, where there was an insufficiency or lack of the proper holders to fit the available cups. This has resulted and can result for numerous reasons, such as an unexpected number of customers for a particular type of drink, and where through error paper cups have been ordered of the wrong type for the available holders. Frequently, too, it is desirable to use both conical and flat bottom paper cups from the same location, and it is uneconomical to maintain a supply of both types of holders, both from the standpoint of monetary investment, and from the standpoint of the space required when the holders are not in use.

It is desirable, therefore, to have a holder capable of properly receiving either a flat bottom or a conical paper cup, and the provision of such a holder is one of the prime desiderata of this invention.

It is also an object of this invention to provide a holder for both flat bottom and conical paper cups, the holder being of the single end type, and having a single cup receiving cavity into which a cup of either type may be positioned.

A further object of the invention is the provision of a holder having a single cup receiving cavity, such cavity being so shaped as to receive either a flat bottom or a conical paper cup and establish positive contact at at least two separate locations, namely adjacent the mouth of the holder, and adjacent the bottom or apex of the cup, so that either form of cup is steadily and securely seated in the holder.

Another object of the invention is the provision of a holder for a paper cup having an insulating dead air space between the cup and holder when the cup is seated in the holder.

Still a further feature of this invention resides in the provision of a holder having a cup receiving cavity therein having a downwardly and

2

inwardly sloping bottom for the cavity, with an opening entirely through the bottom, whereby the apical portion of a conical paper cup may project through the opening, while the rim at the base of a flat bottom cup may seat securely at the outer annular edge or margin of the bottom.

While some of the more salient features, characteristics and advantages of the instant invention have been above pointed out, others will become apparent from the following disclosures, taken in conjunction with the accompanying drawing, in which—

Figure 1 is a pictorial elevational view of a holder for paper cups embodying principles of the instant invention, and indicating in dotted lines the positioning of a conical paper cup in the holder;

Figure 2 is a central vertical sectional view through the holder of Fig. 1, showing a conical paper cup in elevation properly positioned within the holder; and

Figure 3 is a sectional view of the holder of the same character as Fig. 2, showing a flat bottom cup in elevation properly positioned within the holder.

As shown on the drawings:

The instant invention may be made of any suitable material, either metal or plastic, and for illustrative purposes a holder molded in one piece from a suitable thermosetting plastic has been selected.

The illustrated embodiment of the invention includes a slightly tapering body portion 1 having a reinforcing bead or rim 2 around the open mouth thereof, and defining interiorly a cup receiving cavity 3. Due to the tapering character of the body wall, the cup receiving cavity gradually decreases in diameter toward the bottom thereof.

Below the body portion 1 is a base portion 4, also preferably tubular in character, and which may be cylindrical, as illustrated, or any other desired configuration, the holder seating upon the bottom edge of the base 4.

Inside the base 4 a bottom or flange 5 is provided for the cup receiving cavity 3. This bottom is preferably inwardly and downwardly sloping, and tubular in character to provide a central opening 6 therethrough. It will be noted that the opening 6 tapers materially, being considerably larger at the top end than at the bottom end. On the upper side thereof, the bottom extends inwardly a slight distance before breaking into the opening 6 to provide an annu-

lar seat or shoulder 7, clearly seen in Fig. 2, for engagement by a flat bottom cup.

In Fig. 2, I have indicated a conical paper cup 8 seated in the holder. It will be noted that the apical portion 9 of the cup projects through the opening 6 in the bottom of the cup receiving cavity, and this apical portion of the cup also establishes positive contact with the walls defining the opening 6 in at least one location therewith. At the same time, it will be noted that the mouth of the holder establishes positive contact with the body portion of the cup, so with at least these two points of contact the cup is stably held in the holder.

As will be noted from the showing in Fig. 2 the apical portion 9 of the cup effects a seal inside the opening 6 and similarly effects a seal at the mouth end of the holder. Thus a dead air space is provided between the holder and cup which is insulating in character and prolongs the cooling time of a hot substance placed in the cup.

In Fig. 3 I have illustrated a flat bottom paper cup 10 positioned in the holder, and in this case, it will be noted that the annular edge or rim 11 at the bottom of the cup seats firmly on the aforesaid interior annular shoulder 7 of the holder. Here, again, there is positive contact between the holder and the bottom edge of the cup, and there is also contact with the wall of the cup at the mouth of the holder. However, as shown in Fig. 3, if the holder is given the same degree of slope or taper as the flat bottom paper cup, there will be contact throughout the length of the cavity wall. In any event, the flat bottom cup is also stably held within the holder.

From the foregoing, it is apparent that I have provided an extremely economical form of holder for paper cups, the single holder accommodating both flat bottom and conical paper cups in the same cup receiving cavity, and requiring no different operation on the part of the operator to insert either form of cup in the holder. The cup receiving cavity and the bottom thereof are shaped so as to establish firm engagement with either form of cup, at at least two locations, and stably hold either form of cup in the holder. It should also be noted that the illustrated holder costs no more to manufacture than a holder capable of receiving only one form of cup. Further, the holder is long lived, easy to handle, and pleasing in appearance.

It will be understood that modifications and variations may be effected without departing from

the scope of the novel concepts of the present invention.

I claim as my invention:

1. In a single cup holder designed to intimately accommodate both flat bottom and conical paper cups, a tubular body portion having an open mouth and the inner wall of which tapers in keeping with the side wall of a flat bottom paper cup, and an inwardly and downwardly tapered tubular flange extending from the bottom of said body portion and forming an annular shoulder to seat a flat bottom cup at the junction line with said body portion, the inner wall of said flange being located and proportioned with respect to the mouth of said body portion as to intimately engage the apical region of a conical paper cup contacting said mouth.

2. In a single cup holder designed to intimately accommodate both flat bottom and conical paper cups, a tubular body portion having an open mouth and the inner wall of which tapers in keeping with the side wall of a flat bottom paper cup, an inwardly and downwardly tapered tubular flange extending from the bottom of said body portion and forming an annular shoulder to seat a flat bottom cup at the junction line with said body portion, the inner wall of said flange being located and proportioned with respect to the mouth of said body portion as to intimately engage the apical region of a conical paper cup contacting said mouth, and a supporting base for said body portion around said tubular flange.

HOWARD HILL.
